UNITED STATES PATENT OFFICE.

VOLNEY E. LARSEN, OF CHICAGO, ILLINOIS.

BELL AND BUZZER ALTERNATOR.

Application filed September 24, 1921. Serial No. 503,024.

My invention has reference more particularly to an attachment for a bell whereby a quiet signal may at will be substituted in place of the bell.

In apartments and houses it is customary to have a bell, which is electrically operated from a button at the door, but as these bells are made to ring sufficiently loud so as to be readily heard throughout the entire 10 house or apartment, it is frequently desirable to eliminate the loud ringing of the bell so as not to disturb a sleeping or sick person, but at the same time have a less audible signal to give warning when anyone is at the 15 door.

The principal objects of my invention are to provide an attachment whereby the loud sounding of the door bell may be eliminated at will and replaced by a less audible signal; 20 to provide attachments whereby a buzzer may be combined with a door bell so that either may be optionally placed in the operating circuit; to permit the attachment to be applied without the necessity of making 25 difficult electrical connections; to construct the device as a unit, with the parts already connected so that it is only necessary to remove one of the wires from the bell and connect it with the attachment; to provide a 30 structure of this character which is mounted in place by attaching same to the terminals of the bell; to provide convenient means which is operable at a distance for selectively placing the bell or buzzer in the circuit 35 and in general to provide an improved attachment of simple form, inexpensive and easily attached for optionally substituting a buzzer in a circuit in place of the bell.

On the drawings—

40 Fig. 1 is a front view of a bell with my invention applied thereto;

Fig. 2, a sectional view taken on the line 2—2 of Fig. 1;

45 Fig. 3, a side view of the insulating connector, which I use for attaching the buzzer to the bell, and

Fig. 4, a wiring diagram of the device.

Referring to the drawings the reference 50 numeral 1 indicates a bell of the usual construction, which has the binding posts or terminals 2 and 3 respectively to which wires 4 and 5 are connected for ringing the bell. The reference numeral 6 indicates a buzzer which in accordance with my invention is to 55 be substituted at will in the ringing circuit in place of the bell and has terminals 7 and

8 with connectors 9 and 10 respectively secured thereto for supporting the buzzer from the terminals 2 and 3 of the bell. The connector 9 is of metal and is formed with 60 a laterally extending slot 11 at the upper end, which is engaged on the binding post 2 and clamped in place by the regular thumb nut 12, and the other connector 10 is of fiber or some other suitable insulating material and has a metal end piece 13 secured thereon, which latter has a laterally opening slot 14, which engages the binding post 3 and is clamped thereon by the regular thumb nut 15. The wire 4 is retained 70 in place on the binding post 2 of the bell when the connector 9 is applied thereto, and this latter being of metal, affords an electrical connection between the binding posts 2 and 7, whereas the wire 5, which was connected with the terminal 3 of the bell is removed when the connector 10 is applied to this terminal and this wire 5 is connected to a binding post 16 carried by the connector 10 intermediate of the ends of the latter 80 and thus insulated, from both the bell and buzzer. The wires 4 and 5, as shown in Fig. 4, are connected with a source of electrical current, such as a battery, transformer or the like as indicated at 17 and has a switch 18 in the form of a push button for temporarily closing the circuit when it is desired to ring the bell or buzzer.

A two-way switch is employed in connection with this device for selectively placing 90 the bell or buzzer in the electrical circuit and is preferably of the pendant type as shown. This switch may be constructed in any suitable form to accomplish the desired purpose, as for example with a shell 19 having an opening 20 at the end through which the triple wire cord 29 extends, and a transversely movable pin or key 21 having a yoke 22 of spring metal secured intermediately to the stem 21 by the bolt 23. A base 24 is 100 fitted snugly in the lower end of the shell 19 and may be held in place by frictional engagement with the shell or by fastening devices such as screws 25, if desired, and this base has a pair of opposed spring contacts 26 and 27 with seats 28 adapted to be engaged by the rounded ends of the arms of the yoke 22. With this construction, when the pin 21 is moved to one extremity of its movement as shown in Fig. 2, the end of one arm of yoke 22 engages the contact 27 forcing the latter downwardly and seating in the 105 110

recess 28 thereof and at the same time, the other arm of the yoke 22 is released from the clip 26. Reverse operation of the pin 21 returns the free arm of the yoke 22 into engagement with the clip 26 and removes the other arm of the yoke from engagement with the clip 27. For limiting the movement of the pin or key 21, each contact member 26 and 27 has the end upturned, as shown, to afford a stop which is engaged by the arm of the yoke 22 when the latter engages in the seat 28.

The wire 30 of the triple cord 29 has one end permanently connected by means of the bolt 23 with the yoke 22 on the pin 21 and the other end connected to the binding post 16, and as the wire 5 of the bell circuit is connected with the terminal 16, a connection is established between the wires 5 and 30 to feed the current to the switch 19, whereby it is communicated to the bell or buzzer depending upon the adjustment of the pin 21 of the switch 19.

A wire 31 of the triple cord 29 has one end connected with the contact 27, as shown in Fig. 2 and the other end permanently connected with the binding post 8 of a buzzer, as shown in Fig. 3 and the other wire 32 of the triple cord has one end connected with the contact 26 as shown in Fig. 2 and the other end connected with the metal piece 13 of the connector 10 as shown particularly in Fig. 3.

The connectors 9 and 10 are preferably fastened onto the terminals 7 and 8 respectively by means of nuts, which are operated by a wrench, so that these connectors are not easily removable and the wires 30, 31 and 32 are also secured to the respective parts 16, 8 and 13 so that they are not readily removed and the structure preferably furnished fully assembled with the pendant switch 19 attached so that in applying the device to a bell, it is merely necessary to release the thumb nuts 12 and 15 and remove the one wire 5, after which the slotted ends of the connectors 9 and 10 are inserted on the binding posts 2 and 3 and the thumb nuts 12 and 15 are then turned down against the ends of these connectors so as to hold the connectors securely in place and the wire 5 from the terminal 3 is then attached to the binding post 16, whereupon the device is ready for operation.

When the yoke 22 is shifted to engage the terminal 27 to which the wire 31 is connected, the bell is cut out of the circuit and the buzzer cut into the circuit and will be operated when contact is made by the push

button 18 and when the switch yoke 22 is shifted in the reverse direction to engage the contact member 26 to which the wire 32 is connected, the buzzer is cut out of the circuit and the bell cut into the circuit so as to be operated. Thus, the bell or buzzer may be selectively operated by adjusting the switch and this switch, being of a pendant type may be located at a point where it is conveniently accessible.

While I have shown and described my invention in a preferred form I am aware that various changes and modifications may be made without departing from the principle of my invention, the scope of which is to be determined by the appended claims.

I claim as my invention:

1. In a device of the class described the combination of a buzzer having a pair of terminals, connecting means for detachably mounting the buzzer on the terminals of an electric bell, said means comprising a conductor on one of the terminals of the buzzer and an insulator on the other terminal of the buzzer, a two-way switch and branch circuit wires leading from the switch respectively to the last mentioned terminal of the buzzer and to a bell terminal connector on the insulator.

2. In a device of the class described the combination of a buzzer having a pair of terminals, a conductor secured to one of the terminals and having means for detachable connection with the binding post of a bell and an insulating member secured on the other terminal of the buzzer and having a conductor adapted to be detachably connected with the other binding post of the bell, a pendant switch having separate wires leading therefrom and connected respectively with the last mentioned terminal of the buzzer and the conductor on the insulator and a feed wire leading through an insulated connector on the insulator to the switch and adapted to be selectively connected by the latter with the branch wires.

3. An insulating connector comprising an elongated body portion formed of insulating material, a binding post on the body and located adjacent one end thereof, said body provided with an opening at the other end for receiving an electrical connection, said binding post having a connector arranged thereon for detachable engagement with an adjacent electrical connector, and another binding post intermediate the ends of the body.

VOLNEY E. LARSEN.
